UNITED STATES PATENT OFFICE

ARTHUR O. WILKENING, OF ST. LOUIS, MISSOURI

DESIGN FOR A LAWN CHAIR

Application filed November 27, 1931. Serial No. 41,890. Term of patent 14 years.

To all whom it may concern:

Be it known that I, ARTHUR O. WILKENING, a citizen of the United States, residing in the city of St. Louis and State of Missouri, have invented a new, original, and ornamental Design for Lawn Chairs, of which the following is a specification, reference being had to the accompanying drawings, forming part thereof.

I claim:

The ornamental design for a lawn chair, as shown.

ARTHUR O. WILKENING.
